UNITED STATES PATENT OFFICE.

GLENN C. SARVER, OF LONE ELM, KANSAS.

MAIL-BAG RECEIVING AND DELIVERING DEVICE.

Application filed April 4, 1925. Serial No. 20,777.

This invention relates to improvements in mail bag receiving and delivering devices and has for an object the provision of means whereby mail matter may be transferred 5 from a station to a moving car and from the car to the station with a minimum amount of shock or impact.

Another object of the invention is the provision of a device of this character which 10 is simple and durable in construction, reliable in use and in which no movable parts extend beyond the side of the car so that danger of damage or injury from this cause is eliminated.

15 With the above and other objects in view, the invention further includes the following novel features and details of construction, to be hereinafter more fully described, illustrated in the accompanying drawings and 20 pointed out in the appended claims.

In the drawings:—

Figure 1 is a top plan view of the invention arranged beside a railroad track and illustrating both the station device and the 25 car carried device.

Figure 2 is an elevation showing the car carried device in position.

Figure 3 is an end view of the subject matter of Figure 1.

30 Figure 4 is an enlarged fragmentary perspective view illustrating the mail bag supporting device in position to transfer a mail bag from the station device to the car.

Figure 5 is a similar view illustrating the 35 mail bag supporting device in position to transfer a mail bag from the car to the station device, the bag being omitted.

Referring to the drawings in detail where- 40 in like characters of reference denote cor- responding parts, the station device or trans- fer mechanism comprises a rotatable member which includes upper and lower frames 10 and 11 respectively, the latter being con- nected by rods or uprights 12 while sup- 45 ported by the rods or uprights is an inter- mediate or guide frame 13. These frames are so connected as to provide a transfer mechanism which may be rotated as a unit and which is mounted upon a vertically dis- 50 posed shaft 14 which extends downward into a hollow standard or casing 15. The lower end of the shaft 14 is connected by suitable gearing 16 with a motor 17, by means of which the transfer member may be 55 rotated. The speedometer 18 may be con-

nected to determine the speed of rotation of the transfer member.

The car which is indicated at 19 has ex- 60 tends longitudinally along its side, a rod 20. This rod is arranged preferably at or near the top of the door of the mail car, while extending oppositely from each side of the door beneath the rod 20 are rods or arms 21, the latter being arranged parallel with the side of the car.

65 The mail bags which are indicated at 22 are adapted to have secured thereto bag sup- porting devices the latter including hook- shaped plates 23 which are adapted to en- gage over the frames 10 or 11 of the transfer 70 member or over the rods 20 and 21. Ex- tending from the hook-shaped plate 23 of each of the supporting devices are spaced arms 24, while loops 25 and a ring 26 serve to connect the mail bag with the supporting 75 devices. Pivots mounted at the outer ends of the arms 24 as shown at 27 are dogs 28, pivotal movement of these dogs in one direction being limited by stops 29 at the outer ends of the arms 24 and stops 80 30 carried by the dogs 28. The dogs are thus normally in position to bridge the space across the outer ends of the arms 24, but extend inwardly in a relatively in- 85 clined position as shown in Figures 4 and 5 of the drawings.

85 The outgoing mail is preferably support- ed upon the upper frame 10, the transfer member being rotated by the motor 17. The speed of rotation of this member preferably 90 conforms to the speed of travel of the car 19, the car preferably being equipped with a speedometer so that when approaching a station, the car may travel at a predeter- 95 mined speed. The transfer member is rotat- ed in the same direction as the direction of travel of the car and during the travel of the latter past the transfer member, ro- 100 tation of the latter will force the dogs over the rod, or, the rod 20 will engage and open the dogs inward so as to pass said dogs and occupy a position between the arms 24, whereupon, the dogs will be closed under the action of their springs. By moving the 105 transfer member in the direction of travel of the train, the force of impact due to en- gagement of the rod and dogs will be ma- terially lessened, as will also the shock at 110 transfer of the bag, as the bag is travelling in the direction of train movement when

transfer occurs. When the bag supporting device reaches the end of the rod 20, the hook-shaped plate 23 will be disengaged from the frame 10 so as to leave the bag suspended from the rod 20.

Mounted at each end of the rod 20 is a pulley 31 around which passes a rope or cable 32, the latter carrying spaced substantially L-shaped arms 33. One of these arms 10 is adapted to engage the bag 22 so that by operating the rope or cable 32, the bag may be drawn along the side of the car to the door for its convenient removal.

The incoming mail, that is, the mail to be delivered at the station is supported by 15 one of the bag supporting devices just described, the hook-shaped plate 23 being engaged over one of the arms 21. As the car approaches the rotating transfer member, 20 the lower frame 11 will engage and force inward the hooks 28 after the manner described in connection with the rod 20 so that the bag supporting devices and bag will be transferred from the rod 21 to the frame 11.

25 The invention is susceptible of various changes in its form, proportions and minor details of construction and the right is herein reserved to make such changes as properly fall within the scope of the appended 30 claims.

Having described the invention what is claimed is:-

35 1. A mail bag transferring device comprising a station mechanism including an annular horizontally disposed rotatable frame, means to rotate the frame, a car carried rod and a bag supporting device adapted to be transferred from the frame to the rod, said device comprising a supporting

hook adapted for removable engagement 40 with the frame, spaced arms extending from the hook, means connecting the supporting device and bag, spring actuated pivotally mounted dogs at the outer ends of the arms to engage the rod and means to limit pivot 45 total movement of the dogs in one direction.

2. A mail bag transferring device comprising a track device including a rotatable annular frame, a car carried device, a bag supporting device carried by the track device and adapted to engage the car carried device to transfer the bag supporting device to the car and means to rotate the frame.

3. A mail bag transferring device comprising a track device including a movable 55 member, a car carried device including a rod extending longitudinally of the car, a bag supporting device carried by the track device and adapted to engage the rod to transfer the bag supporting device to the car and means included in the track device to move the movable member.

4. A mail bag transferring device comprising a movable track device including a movable member, a car carried device including a rod extending longitudinally of the car, a bag supporting device carried by the track device and adapted to engage the rod to transfer the bag supporting device to the car, means to move the movable member 65 and manually operated means to engage the bag supporting device and move the latter longitudinally of the rod after transfer has been effected.

In testimony whereof I affix my signature.

GLENN C. SARVER.
